LATHER GENERATING DEVICE

Filed May 2, 1931

FIG. 3.

Inventor
JOSEPH LACH

By *Clarence A. O'Brien*
Attorney

UNITED STATES PATENT OFFICE

JOSEPH LACH, OF ENGLEWOOD, NEW JERSEY

LATHER GENERATING DEVICE

Application filed May 2, 1931. Serial No. 534,658.

The present invention relates to new and useful improvements in lather generating devices.

It is the primary object of the present invention to equip a lather generating device with means for heating the liquid which enters into the operation of generating lather.

It is a further object of the invention to provide a lather generating device which will be in the form of a self-contained unit and which will, therefore, be readily transportable.

It is a still further object of the invention to provide a device which will generate a lather of the desired consistency in a rapid and highly efficient manner.

It is a still further object of the invention to provide a device which may be readily disassembled into its several parts for the purpose of cleaning thereof.

With the above and other objects in view which will be apparent as the nature of the invention is better understood, reference will be had to the accompanying drawing, where-

in;

Figure 1 is a view in side elevation of a lather generating device constructed in accordance with the present invention.

Figure 2 is a vertical sectional view of the device, and;

Figure 3 is a horizontal sectional view thereof.

Referring more specifically to the drawing, the device comprises a receptacle 5 which may be constructed from hard rubber, bakelite or other similar material, although other materials may be employed if desired. The receptacle has a neck portion 6 and this neck portion is adapted to be closed by means of a suitable stopper 7.

The reference character 8 designates a discharge nozzle for the lather, and as best illustrated in Figure 2, this discharge spout is removably secured in the stopper 7 by having a threaded engagement therewith.

The reference character 10 designates an immersion heater which is preferably of the electrical type, and said immersion heater also has screw threaded engagement with the stopper 7 as designated at 11 in said Figure 2.

A suitable electrical conductor 12 is attached by means of a suitable coupling 13 to the heater 10 and furnishes the power therefor.

Air is introduced into the receptacle 5 by means of a tube or the like 15 and this tube 15 has its lower end spaced but a slight distance from the bottom of the receptacle 5. The upper end of the tube 15 has threaded engagement as at 16 with the stopper 7 and the upper extremity of said tube 15 projects as at 18 slightly beyond the upper face of the stopper 7.

Air is supplied by means of a pump or the like 20 and said pump comprises a cylinder 21 in which is mounted for reciprocation a piston 22. Interposed between the piston 22 and the lower end wall of the cylinder 21, there is a coil spring 23 which tends to maintain the piston in the intermediate position in which it is shown in Figure 2.

The piston 22 has a piston rod 26 slidably mounted in an opening in the upper end of the cylinder 21 and the upper end of the piston rod 26 is provided with an operating head 27. Leading from the bottom end of the cylinder 21, there is a rigid tube 28 and the upper end of this tube extends up to a position approximating the location of the stopper 7 as indicated at 29 in Figure 2. Connecting the upper end of the rigid tube 29 with the upper end 18 of the tube 15, there is a flexible tubular member preferably in the form of a rubber hose 30.

The top cylinder 21 is preferably carried by the receptacle 5, and is secured thereto by means of bands or the like 33 which substantially surround the receptacle 5, and are shaped to conform to the shape of the cylinder 21. The free ends of the bands are secured together by any suitable fastening means for example, bolts or the like 35 having nuts 36 which bolts pass through the free ends of the bands 33.

The operation of the device is as follows:

Upon operation of the piston 22 in the cylinder 21, air under pressure is forced through the tubes 28, 30 and 15, into the receptacle 5. It is to be understood that the receptacle 5 is filled with suitable liquid either in the form of liquid soap, or ordinary

water with soap, powder or a cake of soap may be employed if desired. The heater is supplied with current by means of a suitable switch not shown and the liquid in the container 5 heated and as the air passes through the liquid in the container, the lather is formed and air pressure carries the same through the discharge nozzle 8 as the lather is generated and pressure is built up in the receptacle 5.

10 Thus it will be apparent that the present invention provides a novel form of lather generator in which the liquid from which the lather is generated may be heated within the receptacle, and in which the generation of lather may be carried on at will.

15 Furthermore, it will be noted that by the construction herein employed the several elements of the device are so mounted with respect to the stopper of the receptacle as to be readily removable for the purpose of cleaning, thus insuring a sanitary device.

20 While the invention has been herein disclosed in a preferred form, it is to be understood that the invention is not to be limited to the specific construction herein shown, and that it may be practiced in other forms without departing from the spirit of the invention.

25 30 Having thus described the invention, what is claimed as new, and what it is desired to secure by Letters-Patent of the United States, is:

35 A lather producing device comprising a receptacle having a restricted mouth, a stopper closing the mouth, said stopper being spaced from the inner end of the mouth, a goose neck pipe passing through the stopper with its lower end flush with the lower end 40 of the stopper, a pipe having its upper end passing through the stopper with its upper end projecting above the stopper and its lower end spaced slightly from the bottom of the receptacle, a pump cylinder vertically 45 arranged, clamps connecting the cylinder with the receptacle in spaced relation, a piston in the cylinder having its stem passing through the top thereof, a vertically arranged pipe having its major portion located in the 50 space between the receptacle and cylinder and having its lower end connected with the lower end of the pump cylinder, and a flexible pipe connecting the upper end of the last-mentioned pipe with the projecting end of the 55 pipe which extends to a point spaced from the bottom of the receptacle.

56 In testimony whereof I affix my signature.
JOSEPH LACH.
